UNITED STATES PATENT OFFICE.

CARL RÖSTEL, OF MAGDEBURG, GERMANY, ASSIGNOR TO GRUSONWERK,
OF SAME PLACE.

BREECH-LOADING FIREARM.

SPECIFICATION forming part of Letters Patent No. 480,627, dated August 9, 1892.

Application filed May 28, 1889. Serial No. 311,870. (No model.) Patented in Germany November 11, 1888, No. 47,222; in Belgium November 29, 1888, No. 84,117, and in France November 29, 1888, No. 194,420.

To all whom it may concern.

Be it known that I, CARL RÖSTEL, a subject of the King of Prussia, residing at Magdeburg, in the Kingdom of Prussia, German Empire, have invented certain new and useful Improvements in Breech-Loading Firearms, (for which I have obtained Letters Patent in Belgium, No. 84,117, dated November 29, 1888; in France, No. 194,420, dated November 29, 1888, and in Germany, No. 47,222, dated November 11, 1888,) of which the following is a specification.

This invention relates to breech-loading firearms, and more especially those wherein firing-pins or hammers are employed; and it consists in combining with the breech-block means—such as a projection—opposing the movement of the block and controlled by the percussive device, which will prevent the movement of the block until the gun has been discharged.

In the use of breech-loading firearms serious accidents are sometimes caused by reason of a cartridge hanging fire and exploding after the breech is opened or during the opening thereof.

The main object of the present invention is to obviate the liability to accidents from this cause by preventing the opening of the breech before the cartridge has been discharged. For this purpose I provide the gun with a catch or locking device, which holds the breech-block in its closed position, and for effecting the disengagement of the said catch or locking device I utilize the recoil or backward movement of the detonating cap of a cartridge which takes place when the powder charge thereof is exploded. It has been ascertained by a long series of experiments that this recoil movement is sufficient to permit of its being practically utilized for the purpose above mentioned. When the detonating cap explodes without firing the powder charge of the cartridge, the said cap, by reason of the small amount of explosive force thus produced, performs a smaller retrograde movement than it does when the entire charge of the said cartridge is exploded, and it is the difference between these two movements that is utilized for the purpose above mentioned.

In carrying out my invention the locking device, which is controlled by the percussive device, is made to engage directly or indirectly with the breech-lowering mechanism, or it is made to control a bolt engaging in the breech and block, or the locking device itself is carried by the block and engages in the breech or reinforce.

Various forms of mechanism may be employed for carrying out the principles of my present invention, some of which will be hereinafter described with reference to the accompanying drawings, in which—

Figure 1 is a vertical section on the line 1 1, Figs. 2 and 5, showing in elevation the inner wall of the breech of a self-cocking gun to which some forms of my present invention are especially adapted. Fig. 2 is a transverse section of the same on the line 2 2, Figs. 1, 3, 4, and 5, the block-lowering crank-arm being shown in elevation. Fig. 3 is a vertical section of the same on the line 3 3, Fig. 2, showing the adaptation of one form of my invention to a self-cocking gun. Fig. 4 is a vertical section on the line 4 4, Figs. 2, 5, and 6, illustrating another form of the invention wherein the locking device indirectly engages the block-lowering crank-arm. Fig. 5 is a horizontal section on the line 5 5, Fig. 4. Fig. 6 is a similar view to Fig. 5, showing the parts in the position which they occupy after the charge has exploded. Fig. 7 is a view similar to Fig. 3, but showing a form of the invention in which the cocking-lever, which works automatically at the lowering of the breech, is engaged by the firing-pin to prevent movement of the lever and through it the block when the charge has not exploded. Fig. 8 is a horizontal sectional view of a gun in the plane of the firing-pin, illustrating a simplified form of the invention in which a bolt carried by the block engages in the side of the breech when the firing-pin is not driven back by the explosion. A push-pin is provided in the wall of the breech for forcing back the firing-pin. Fig. 9 is a horizontal sectional view of a form of the invention in which a rocking lever carried by the block is adapted to engage in and be disengaged from the reinforce when the gun hangs fire and is

discharged, respectively. Fig. 10 is a vertical section in the plane of the side of the block, illustrating the adaptation of the invention to a gun employing a firing-hammer. Fig. 11 is a vertical section on the line 11 11, Fig. 13, illustrating a device of modified form. Here the cocking of hammer is effected automatically at the lowering of the breech by rotating the hammer-shaft, as hereinafter explained. Fig. 12 is a similar view illustrating another form wherein the firing-hammer causes a spring-arm to engage the breech-lowering crank-arm when the charge fails to explode. Fig. 13 is a horizontal section on the line 13 13, Fig. 11, showing the manner of attaching the cocking crank-arm illustrated in Fig. 2 to a firing-hammer. Fig. 14 is a view similar to Fig. 5, wherein a firing-hammer is substituted for a firing-pin.

Referring to Figs. 1 to 7, inclusive, A is the reinforce, and B the breech-block, which slides vertically therein. In order to support and operate the breech-block, a shaft a^2 , Figs. 2, 4, 5, 6, 12, and 14, journaled in the side of the reinforce, is provided at its inner end with a crank-arm a , carrying a pin a' , which engages in an inclined groove a^4 in the breech-block, Fig. 4, while at its outer end said shaft is provided with a controlling-handle a^3 . (See Fig. 2.) If the shaft a^2 be rotated in the right direction by its handle a^3 , the crank-arm a will swing forward, with its pin a' , in the inclined groove a^4 of the block, whereupon the block will be allowed to descend. By reversing the movement of the handle the block is returned.

b is the percussive device, which in Figs. 2 to 9, inclusive, consists of a firing-pin projected by a spiral spring, but in the remaining figures consists of a hammer swung by a spiral spring, as indicated in Fig. 13, or by any suitable means ordinarily used. In order to automatically cock the firing-pin as the breech is lowered, a shaft d , mounted in the breech-block, is provided with a cocking-lever d' , extending upward and entering a slot in the firing-pin b , Figs. 2, 3, and 7, while a crank-arm d^4 , Fig. 2, extends upward from the left-hand end of said shaft and has a pin d^3 , which engages a slot d^2 , Figs. 1 and 2. This slot is formed in the left wall of the breech and inclined slightly to the perpendicular. When the block is lowered, the pin d^3 on the crank-arm d^4 follows the groove d^2 , whereby the crank-arm and cocking-lever are swung to the rear and the firing-pin withdrawn sufficiently far to permit the block e' , Fig. 3, to engage the percussive device and retain it in cocked position. When the breech-block is raised into normal position, as after the cartridge is inserted, the cocking mechanism also returns to normal position, but leaves the percussive device cocked, inasmuch as the cocking-lever works in an elongated slot in said device. In order to automatically cock the firing-hammer, if such be desired, the cocking crank-arm d^4 , having the pin d^3 , which engages in

an inclined or cam groove d^2 , as described with reference to Figs. 2 and 3, may be applied directly to the transverse shaft or boss of the firing-hammer, as hereinafter described with reference to Fig. 13. The firing-pin b is retained in its cocked position by means of a block e' , pressed up by a spring-piston e , and the said block is adapted to engage in front of a collar b' on the firing-pin to keep said pin in cocked position.

By referring to Fig. 3 it will be seen that the block e' is adapted for engagement by its two shoulders behind the collar b' , as well as in front of it, such engagement behind being only permitted, however, when the pin is in its foremost position and in contact with the detonating cap. When the block is thus engaged behind the collar, the breech-block cannot be lowered, inasmuch as the firing-pin cannot be withdrawn, the cocking-lever d' and its rigidly-connected operating crank-arm d^4 cannot be moved backward, and the breech-block is locked by engagement of the inclined groove d^2 in the reinforce by the pin d^3 on said operating crank-arm and cannot be moved until the block e' is moved downward. If, however, the powder charge is exploded, the action of the gases thus generated will drive backward the detonating cap and through the said detonating cap the firing-pin b . This action being instantaneous, the collar b' of the firing-pin slides over the block or piece e' before the piston e can be released, and when it is released the firing-pin rests out of engagement with the block e' . Should the powder charge not explode, the block or piece e' engages with the rear side of the collar b' of the firing-pin and the gunner will be unable to lower the breech immediately, but will have to pull the trigger f , and thus draw down the rod e first. This will notify him of the danger of a possible hang-fire, and he will therefore wait a reasonable time before opening the breech. It is obvious that by these means even during the most rapid firing the hanging fire of a cartridge cannot fail to be noticed, and complete protection is thus insured against accidents due to this cause.

Figs. 11 and 13 illustrate one mode of applying the above-described form of my invention to a gun having a firing-hammer which is operated by the reaction of a spring, which is compressed by the automatic cocking of the hammer by a cocking crank-arm attached directly to the transverse rock-shaft or boss and adapted to be moved back at the lowering of the block by the engagement of its pin in a groove in a similar manner to that described with reference to Figs. 1 and 2, as will hereinafter appear. The rock-shaft or boss b^3 of the hammer b is provided with two recesses or notches b^4 . Should the cartridge hang fire or fail to explode, the head e' of the rod e , being caused by the spring to engage in the lower recess or notch of the said boss, will prevent the turning of the hammer. Consequently the breech cannot be opened without

first pulling the trigger and thus disengaging the head e' from the notch in the boss b' . If, however, the hammer is thrown back sufficiently by the recoil of the detonating cap to allow the edge of the said recess or notch to pass in front of the head e' before the trigger can be released by the gunner, the hammer can be cocked and the breech opened, and the head e' , falling into the upper recess or notch 10 in the boss b' , will retain the hammer in the cocked position.

In order to provide for the automatic cocking of the hammer b , Fig. 11, a crank-arm d^4 is employed, as described with reference to 15 Figs. 1 and 2 and shown by dotted lines in Fig. 11.

The firing-hammer is provided with a transverse rock-shaft b^3 and an operating-spring b^5 , coiled upon the rock-shaft and having its 20 ends fixed in any suitable manner. The hammer and cocking crank-arm are mounted rotatably upon a common axis b^6 , and they are provided with lugs b^7b^8 , bearing such relation to each other that the movement of the crank-arm to the rear will cock the hammer, while a return of the crank-arm to normal position does not affect the hammer. When the block 25 is lowered, the crank-arm is moved to the rear by the engagement of its pin d^3 in the groove d^2 , and the hammer is moved backward and downward by the crank-arm until the head e' engages in the upper one of the notches. When the block is returned to normal 30 position, the crank-arm also returns, but the hammer remains cocked until released by means of the pull-rod or trigger f .

The arrangement shown in Fig. 7 is also based upon the same assumption that the firing pin or hammer is automatically cocked 40 during the opening of the breech. Here the projection opposing the block's movement is a shoulder e^2 on the lever d' , which cocks the firing-pin. This lever is controlled by the firing-pin through the medium of a horizontal shoulder e^2 on the lever, which engages a corresponding projection b^2 , formed on said firing-pin and forming the lower side of the recess of the firing-pin. Now, since the swinging of the lever d' on its shaft causes 45 the shoulder e^2 to move downward as well as rearward, its engagement with the projection prevents the swinging of said lever d' , so that should a cartridge hang fire or fail to explode and drive the firing-pin slightly 50 to the rear the cocking-lever, which is moved by the lowering of the block and whose hooked or shouldered end engages in the firing-pin, cannot move, and it will therefore prevent the breech being opened until the firing-pin is drawn back by hand. Should, however, the firing-pin be pressed back by the detonating cap, the rear surface of the shoulder 55 e^2 does not engage the projection b^2 and the breech can be opened and the firing-pin 60 cocked in the usual manner by engagement of the lever-head with the forward end of the projection b^2 on the firing-pin.

The arrangements shown in Figs. 4, 5, 6, 8, 9, 10, 12, and 14 are not dependent upon the automatic cocking of the firing-pin or hammer by the movement of the breech-block, but are adapted for use in connection with percussive devices operated in any suitable manner. In these cases the lowering is controlled by causing the rod, bar, or other projection to engage or lock some other part of the gun between which and said rod or bar there is relative movement during the opening of the breech. 70

Figs. 4, 5, and 6 show an arrangement in 80 which is employed a plate-spring e^3 , fixed at its forward end in the breech-block and adapted to lie normally against the face of said block, but to engage with the upper end of the lowering crank-arm a when forced outward by the block h' . The spring e^3 has a head l , which is fitted in a recess in the block and kept from turning by a flat face, which fits against the block. The lever is retained in its position in the recess by means of a vertical shaft k , which passes through the block and lever with freedom of turning. The block h' slides in a transverse recess in the breech-block and acts upon the spring e^3 through the medium of a horn h , and it is provided at its 90 inner end with a beveled shoulder, which is engaged by a correspondingly-beveled edge of the collar b' on the firing-pin b when said firing-pin is in its projected position. When the firing-pin b is released and projected forward, it forces the block h' , and through it the spring e^3 , outward, so that said spring e^3 engages the block-lowering crank-shaft a and prevents movement of the same. When the firing-pin b is moved backward, the block h' 100 is released and the spring e^3 resumes its normal position against the side of the breech-block by its own elasticity. Should the cartridge hang fire or fail to explode, the firing-pin remains in engagement with block h' and the spring e^3 in front of the crank a , so that the latter cannot be moved. Consequently the breech cannot be opened until the firing-pin is drawn or pushed back by hand sufficiently to allow the bolt or catch h' to slide in 110 front of the collar b' . 115

In order that the block h' may be pushed in by hand, I provide the spindle k with a suitable crank-handle g at its lower end and an arm or projection i , fixed just beneath the head of the spring-lever e^3 , and I provide a downwardly-extending pin m on the block h' , with which the arm i engages. If the crank-handle g , which extends to the rear of the spindle, is moved inward, the arm i forces 120 back the block h' through the medium of the pin m and the spring e^3 is permitted to resume its normal position. Should, however, the powder charge explode at the projecting of the firing-pin, the detonating cap will force 130 back the firing-pin, with its collar b' , so that the bolt h' will move in front thereof, and the spring e^3 will not, therefore, interfere with the movement of the crank a and the breech is 125

free to be opened. It is not absolutely necessary to place the collar b' on the forward end of the firing-pin, as it may with more or less advantage be placed in any other position on the said firing-pin.

The above-described form of locking device may be readily applied to a gun employing a firing-hammer.

Fig. 15, which is a view of a horizontal section just above the firing-hammer, represents such a use of the device. Here the firing-hammer is provided with a collar b' and the beveled shoulder on said collar, which engages the block b' when the hammer is in its projected position. It is obvious that the operation of this device is similar to that shown by Figs. 4, 5, and 6.

Fig. 8 illustrates a much simpler arrangement or modification of the locking device above described. In this case the breech-block itself and not the crank is arrested or locked by the device e' . e' represents a bolt, which works in a perforation in the side of the breech-block and is adapted to be forced outward by the percussive device into all of the breech, so as to prevent relative movement between the breech-block and breech. The bolt has a spring for projecting it inward when the firing-pin offers no resistance. The collar b' on the firing-pin and the bolt e' have the corresponding beveled shoulders, which enable the pin to force the bolt outward, as hereinbefore described with reference to analogous forms. Should the cartridge hang fire or miss fire, the bolt e' is forced to enter the recess formed in the wall of the breech by the collar b' of the firing-pin b , and this prevents movement of the breech-block. Therefore before the breech can be opened the rod or catch e' must be pushed back, and this operation is effected by means of a push-pin g' , which projects through the side of the breech and engages by its inner end the outer end of the bolt. The bolt e' may thus be moved inward, the firing-pin b being forced back by the correspondingly-beveled shoulders on the said bolt and the collars b' of the said firing-pin. Should the cartridge explode and the detonating cap force back the firing-pin, the rod or catch e' will be disengaged from the wall of the breech by its own spring.

Fig. 10 shows a modification wherein the principle, described with reference to Fig. 8 is applied to a gun having a firing-hammer. The hammer is presumed to be actuated by a suitable spring and is cocked in any suitable manner well known in the art. The bolt e' is engaged at its inner end by a cam b^4 on the transverse shaft b^3 of the firing-hammer and forced outward into a suitable recess in the breech when the hammer is at its forward limit, but is free to be forced slightly inward by its spring when the hammer is moved slightly rearward. Should the cartridge hang fire, the cam b^4 , formed on the shaft of the firing-hammer, forces the bolt e' into the recess

provided in the wall of the breech. If the firing-hammer is slightly thrown back by the detonating cap, the cam b^9 is moved away from the bolt e' , which is then drawn out of the said recess by its spiral spring. The cam b^9 and the front surface of the bolt e' are formed with beveled surfaces, so that the latter can be pressed backward to unlock the breech-block. This is accomplished by a downwardly-extending arm g^6 , by which the bolt can be pressed in and the firing-hammer caused to move slightly.

In Fig. 9 a rocking lever e^4 , working in a recess in the block to one side of the firing-pin, is made to engage in or is withdrawn from a recess in the rear of the breech. The lever e^4 is pivoted at e^8 and provided with ears e^9 , which are engaged by a projection e^{10} on the rear of the firing-pin. The lever is further provided with a pin e^{10} on its lower end, which engages in a suitable recess in the breech. When the firing-pin is projected, it engages the forward one of the two ears e^9 and causes the pin e^{10} to enter the recess in the breech. Should the cartridge explode, the firing-pin will be driven backward sufficiently to disengage the pin e^{10} by engagement with the rear one of the two ears. If the charge fails to explode, the pin will remain in the recess in the breech and the block cannot be lowered until the firing-pin is drawn back by hand. This last-mentioned operation may be effected by cocking the gun—as, for instance, by drawing back the pin b by the eye b^{11} , formed on its rear end.

Fig. 12 is a modification in which the locking rod or catch is replaced by a plate-spring e^{12} , secured at e^{13} and resting normally across the transverse shaft b^4 of the hammer. A cam b^9 on the shaft b^3 of the firing-hammer b engages the spring e^{12} when the hammer rises to the striking position. The end e^{14} of the spring is upturned and is adapted to engage in a recess a^6 in the crank-shaft a , that operates the breech-block. A lever g^3 is operated by hand to disengage the end e^{14} by pressing through the medium of short arm g^4 , which is formed integral with said lever, down upon the plate-spring e^{12} , which in turn presses upon the cam b^9 and causes the hammer to turn backward. If the charge fails to explode, the hammer remains in such a position as to cause the spring e^{12} to engage in the notch in the block-lowering crank. If, however, the charge explodes, the hammer falls back to such position as will allow the spring to resume its normal position, which is with the upturned end just below the notch.

The examples of the application of this invention might be increased, as the said invention can with slight modifications be applied to any movable part in any description of breech mechanism in breech-loading firearms. It is not, however, necessary to describe any further modifications, as they are all similar in the main feature—that is to say, that the

firing-pin or hammer, actuated by the recoil movement of the detonating cap, disengages a rod, catch, or spring or other locking device, such rod, catch, spring, or other locking device remaining operative if a cartridge hangs fire, and thereby preventing the opening of the breech.

Having thus described my invention, the following is what I claim as new therein and desire to secure by Letters Patent:

1. In a breech-loading gun, the combination of the breech, the breech-block working on the breech, the percussive device, and a locking device for preventing the movement of the block, controlled by the percussive device, substantially in the manner and for the purposes set forth.

2. In a breech-loading gun, the combination, with the breech and the breech-block, of the locking device carried by one and engaging in the other and the percussive device engaging the locking device when in its projected position, thereby causing the locking of the block, substantially as set forth.

25 3. The combination of the breech, the breech-block, the percussive device, the lowering mechanism, the crank-arm adapted to rotate with the movement of the block and engaging the percussive device to cock it, and means controlled by the percussive device for opposing the movement of the cocking-arm, substantially as set forth.

30 4. The combination of the firing-pin or other percussive device, the pin for retaining the percussive device in cocked position and also adapted to lock it when in contact with the cartridge, and the breech-lowering mechanism having working connection with the per-

cussive device, substantially as and for the purpose set forth.

5. In a breech-loading gun, the combination, with the breech, breech-block, and lever for operating the breech-block, of the percussive device, the pin for retaining said percussive device, said pin being adapted to engage the 45 percussive device when in contact with the cartridge, and a spring-arm engaging the lowering mechanism and controlled by the retaining-pin, for the purpose and in the manner explained.

50 6. In a breech-loading gun, the combination, with the breech-block, of the lowering mechanism engaging the breech-block and having an arm which engages the percussive device to cock it, said arm and percussive device 55 having a corresponding hook and recess which engage to prevent the movement of the block until the percussive device is repelled by the force of explosion, substantially as explained.

7. In a breech-loading gun, the combination, with the breech and block, of a retaining-pin engaging the block and controlled by the percussive device, whereby the block is prevented from moving until the percussive device is repelled by the force of explosion, substantially as set forth.

60 8. In a breech-loading gun, the combination of the breech, the breech-block, and the device for locking the block in the breech, constructed and arranged to be unlocked by the 65 recoil of the cap of the cartridge, substantially as shown and set forth.

CARL RÖSTEL.
